(57) **CLAIM**

We claim, the ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is a second image in a sequence thereof;

FIG. 3 is a third image in a sequence thereof;

FIG. 4 is a fourth image in a sequence thereof;

FIG. 5 is a fifth image in a sequence thereof;

FIG. 6 is a sixth image in a sequence thereof;

FIG. 7 is a seventh image in a sequence thereof;

FIG. 8 is an eighth image in a sequence thereof;

FIG. 9 is a ninth image in a sequence thereof;

FIG. 10 is a tenth image in a sequence thereof;

FIG. 11 is an eleventh image in a sequence thereof;

FIG. 12 is a twelfth image in a sequence thereof;

FIG. 13 is a thirteenth image in a sequence thereof;

FIG. 14 is a fourteenth image in a sequence thereof;

FIG. 15 is a fifteenth image in a sequence thereof; and,

FIG. 16 is a sixteenth image in a sequence thereof.

The subject matter in this patent includes a process or period in which an image changes into another image. This process or period forms no part of the claimed design.

The broken lines illustrate a display screen or portion thereof, and form no part of the claimed design.
